AUTOMATIC SWITCH FOR TELEPHONE SYSTEMS.

1,169,387.

Specification of Letters Patent. Patented Jan. 25, 1916.

Application filed July 16, 1913. Serial No. 779,350.

To all whom it may concern:

Be it known that we, KNUT ERIC ERICSSON and GUSTAF WILHELM DAHLSTRÖM, citizens of Sweden, residing, respectively, at Saltsjö-Storängen and Stockholm, Sweden, have invented certain new and useful Improvements in Automatic Switches for Telephone Systems, of which the following is a specification.

10 This invention relates to an arrangement for automatic switching in telephone systems, and in such manner that as soon as the speaking currents flow in the one direction, no reaction from said currents upon 15 the apparatus belonging to the same station can take place.

The invention is of particular importance in telephone systems with magnifiers, where reactions of this kind easily produce disturbing sounds.

The invention is particularly characterized by the telephone currents, arriving from one direction, themselves directly or indirectly acting upon a relay, which effects 25 the switching. As soon therefore, as speech from either station has continued for a certain time—which easily can be made so short that practically nothing of the speech is lost—the line is coupled for speech only 30 in the one direction, and remains so until the first speaker makes a pause of sufficient length to enable the reversal of the switch. If then speech commences from the other speaker that apparatus will in turn, after 35 a short interval of time, be automatically set or coupled so as to exclude currents arriving from the first line, and so on. The arrangement can either be such, that the speaking currents themselves, or currents induced by 40 them—which then must be alternating currents—act upon a nonpolarized relay, which, directly effects the coupling, or else such that said first named relay only effects a breaking at a contact point in a local circuit,

45 in which a second relay acting upon the switch is coupled, and in this latter case, the currents acting upon the first named relay can either be alternating or undulating currents. In such case, where the arrangement 50 is used in connection with magnifiers, it is preferable to use the intensified currents from said magnifiers to actuate the switch.

A few embodiments of the invention are shown on the annexed drawings, where—

55 Figure 1 shows diagrammatically a sta-

tion with magnifiers arranged for disconnection of the one magnifier; Fig. 2 corresponding diagram for one-half of a station, arranged for disconnecting. Figs. 3 and 4 show modifications of the arrangement in 60 Fig. 1.

In Fig. 1, L_1 and L_2 are the two lines comprising two wires or branches, through which speaking currents alternately arrive to the magnifier station. The current from L_1 65 passes first through a switch a_1, b_1, c_1 , which normally has such position that a_1 makes contact with b_1 , whereby the current must pass through the magnifier telephone h_1 and back through the other branch of the line 70 L_1 . The microphone m_1 of the magnifier is inserted in a local circuit, which also embraces the primary winding at two transformers p_2 and r_2 . The secondary winding of the first named of these, through the relay-electromagnet E actuates, as will be later 75 more fully described, the local circuit for the time-relay R , with the result, that on this side of the station, the switch a_2, b_2, c_2 after a short interval is reversed so that a_2 80 makes contact with c_2 instead of with b_2 , against which it normally abuts. As soon as this reversal is accomplished, currents can be induced in the secondary windings of the other transformer r_2 and flow out in the 85 linewidth L_2 . Currents that arrive through this line under these conditions, however, can only circulate through the transformer r_2 and the line itself, unable to affect any magnifier, or thereby the line L_1 . Neither 90 can currents induced in the magnifier h_1, m_1 and transformer r_2 in any manner affect the line L_1 through the magnifier h_2, m_2 , whereby otherwise disturbing sounds could be produced.

When speech through the line L_1 ceases, the switch a_2, b_2, c_2 , actuated by its timerelay, returns to the normal position with a_2 in contact with b_2 . If now speaking currents arrive through the line L_2 , these will 100 induce magnified currents through the magnifier h_2, m_2 , which in turn affect both the transformer r_1 , producing currents through the line L_1 , and also the transformer p_1 , whereby through a time-relay, in the manner similar to that just described, the switch a_1, b_1, c_1 is reversed, preventing currents that may then arrive through the line L_1 from 105 passing the magnifier h_1, m_1 .

The arrangement of the local circuit L_1 , 110

l_2 , fed from the secondary windings of the transformers p_1 and p_2 respectively, and actuating the electromagnet E, as also the circuit L is shown in Fig. 1. Wires such as 5 l_1 and l_2 connect each of the transformers p_1 , p_2 with an electromagnet E the armature of which is in the shape of a diaphragm M, and carries an arm A, which latter can be arranged so that the amplitudes of the vibrations of its free end are greater than that of the diaphragm—for instance by fixing the arm both to the center and edge of the diaphragm, as shown in the figure. At the free end of the arm is a contact piece K, 10 against which rests one end of a lever H, counterbalanced by the weight V.

Details of the mechanism just described may be varied at will without departing from the spirit of my invention.

20 The diaphragm M, A, and lever H form part of a local circuit which includes the time-relay previously mentioned, and said relay, in its construction as shown, involves also a movable core J in aforesaid solenoid, 25 further a counterweight G, connected to the core J by means of a flexible band led over a pulley D, and in a manner tending to raise the said core, and finally a shoulder N upon the core J, which actuates the switch 30 a_1 b_1 c_1 or a_2 b_2 c_2 generally designated by a , b , c , previously described. Under influence of the normally closed circuit through the battery B etc. the core J is normally held down so that the shoulder N presses 35 the arm a , against the contact b . When, however, the diaphragm M begins to vibrate and make the contact between K and H intermittent, the attraction of the solenoid R upon the core J generally becomes 40 sufficiently reduced to enable the counterweight G to lift the core so as to permit the arm a —for the purpose here supposed to be resilient—to rise and press against the upper contact c . The inertia of the movable 45 parts J, G, etc., can of course easily be adjusted so that the reversal takes place in a suitable interval of time, that is an interval such that nothing essential of the speech is lost, and such that short pauses in the 50 speech—for instance less than 0.5—1 second, will not cause a reversal of the switch.

The core J should be sufficiently mobile to enable its shoulder N, during normal speech, to rise higher than the position actually required for contact between the arm a and the upper contact c . This is of importance in order that minor irregularities in the speech, which may tend to lower the core, should not cause an interruption between a and c ; on the other hand the mobility of the core must not be such as to bring it into continual oscillation. Besides this method of adjusting the mass of the core and counterweight etc. in suitable relation to the active forces, a frictional resist-

ance can be introduced in order to reduce the mobility of the parts. For this purpose, as for instance shown in the flexible band connecting core and counterweight, besides being led over the pulley D, can be arranged 70 to pass over two fixed rods or pins F, which eventually could be adjustable for the purpose of regulation, but of course any other device with the object in view can be used.

It should be clearly understood, that such 75 an alternative arrangement of the time-relay and local circuit can be made or used, whereby the latter is normally open instead of closed, when the former in inert condition will press the arm a against the contact b . In such case the vibrations of the diaphragm M will intermittently close the circuit at the point of contact of the parts K and H, when the core J, will be attracted by the solenoid R with sufficient average 80 strength to effect the reversal of the switch.

In the arrangement as shown diagrammatically in Fig. 2 and supposed to correspond to one half of that in Fig. 1—with corresponding parts similarly lettered, but 85 without indices—the switch is arranged in a somewhat different manner, besides which the connections are such that the magnifier is short-circuited instead of being cut out. The result of this remains the same as in 90 Fig. 1. The incoming line to the switch is here connected with a member a , carrying a contact piece for a sliding-contact, which latter in turn is connected with the contact b . The sliding-contact is held by the time-relay normally in its upper position and rests then against a contact arm d , which by means of a spring or similar arrangement tends to move downward. The currents arriving through the line L, will then 100 pass the telephone apparatus h of the magnifier, while the transformer r is short-circuited. When on the other hand the time-relay is affected in the manner previously described, it will permit the sliding-contact to drop, and with it the arm d , so far that the latter comes in contact with c . The sliding-contact continues further until the contact b is freed from the arm d , and from here then the connections are such 110 that the transformer r is in circuit, while the telephone apparatus h is short-circuited. 115

In Fig. 3 the switch is of the same type as in Fig. 1, but otherwise the connections are so altered, that the same primary winding is used for the transformer r , which transmits speaking currents to the line, as also for the transformer p , which serves the time-relay. In Fig. 4, the last mentioned transformer is left out altogether, and the 120 line l , to the diaphragm-electromagnet E, E, is branched directly from the poles of the secondary winding of the transformer r .

Having now particularly described and ascertained the nature of our said inven- 125 130

tion and in what manner the same is to be performed, we declare that what we claim is:

1. In a telephone repeating system in combination, two lines each adapted to either send or receive, a switch relay for each line, a line switch for each line, the relay acting upon the line switch and arranged to switch each line so as to allow the speaking currents to flow in the one or the other direction only, an auxiliary circuit for each line, a magnifier associated with each line for connecting each auxiliary circuit to the other line circuit so as to obtain magnified speaking currents in the said auxiliary circuits, and intermediate means between the switch relay of one line and the said auxiliary circuit of the other line for operating said relay of one line by the said magnified currents from the magnifier of the other station.

2. In a telephone repeating system in combination, two lines each adapted to either send or receive, a switch relay for each line, a line switch for each line, each relay acting upon a line switch and arranged to switch each line so as to allow the speaking currents to flow in one or the other direction only, an auxiliary circuit for each line, a magnifier for connecting each auxiliary circuit to the other line circuit so as to obtain magnified speaking currents in the said auxiliary circuit, and intermediate means between the switch relay of one line and the said auxiliary circuit of the other line for operating said relay of one line by the aid of the magnified currents from the magnifier of the other line, said auxiliary circuit being inductively connected to the relay.

3. In a telephone repeating system in

combination, a receiving line, a sending line, an auxiliary circuit for each line, a magnifier for each line, a line switch for each line, means for operating said switch for one line by the magnifier for the other line, said line switch short circuiting the magnifier of its own line in one of its positions.

4. In a telephone repeating system in combination, a receiving line, a sending line, an auxiliary circuit for the sending line, a line switch for each line, a magnifier for each line, a switch relay, said relay being adapted to operate a line switch, means for operating said relay by the aid of the magnified currents of the other line, a transformer for said sending line, said lineswitch short circuiting the magnifier of the sending line in one position, and short circuiting the secondary of said transformer in its other position, the primary of said transformer being inserted in the magnifier circuit of the other line.

5. In a telephone repeating system in combination, a sending line, a receiving line, a switch for each line, a magnifier for each line, two transformers for each line, an interrupter for each line, and a switch relay for each line, the secondary of one of the said transformers being in circuit with said interrupter, each of said line switches connecting the secondary of the remaining transformer of the other line with the two branches of its own line, and said switch simultaneously short circuiting the magnifier of its own line.

In testimony whereof we have affixed our signatures.

KNUT ERIC ERICSSON.
